AIR CLEANER AND SILENCER ASSEMBLY

Herbert G. Kamrath, Flint, Mich., assignor to
General Motors Corporation, Detroit, Mich., a
corporation of Delaware

Application September 12, 1936, Serial No. 100,538

2 Claims. (Cl. 183—44)

- This invention relates to air cleaner and silencer assemblies of the type disclosed in my application Serial No. 50,745 which was filed on November 20, 1935 and has for its principal object to improve such assemblies by making the air cleaning element easily removable and replaceable so as to facilitate servicing of it and to do this in such a way as to reduce the cost of the assemblies.
- For a better understanding of the nature and objects of this invention, reference is made to the following specification wherein there is described the preferred embodiment of the invention which is shown in the accompanying drawing.
- In the accompanying drawing:
- Figure 1 shows, partly in side elevation and partly in longitudinal section, an air cleaner and silencer assembly in accordance with my invention.
- Figure 2 is a fragmentary top plan view of the assembly shown in Figure 1 with the cap and filter element removed.

Figure 3 is an exploded view on a reduced scale of the assembly shown in the preceding figures.

The assembly shown in the drawing consists essentially of a body 10, a filter element 11 and a domed cap 12.

The body 10 includes a cylinder 13 over whose lower end there is secured a head 14. Over the upper end of the cylinder 13, there is secured an element 15 which is shaped generally like a brimmed hat with an annular channel 16 in its brim and a centrally disposed orifice encircled by an inwardly projecting flange 17 in the top of its crown. Disposed below the crown of the element 15 and the flange 17 which encircles the orifice in the top of it is an element 18 whose outer margin is joined to the inner margin of the brim of the element 15. The element 18, with the brim of the element 15, constitutes the upper head of the cylinder 13 and, with the crown of the element 15, defines an inwardly opening recess 19 which constitutes what is known as a hiss gap.

Through the body formed by the cylinder 13 and its upper end lower heads, there extends a duct which consists of telescopically related tubes 20 and 21 which are aligned with the orifice in the top of the crown of the element 15. The tube 20 extends through an opening in and is joined to the lower head 14 with its upper end disposed about half way between the upper and lower heads. The tube 21 extends through an opening in and is joined to the element 18. It is of smaller diameter than the tube 20 and extends well into

and defines with it an annular aperture 22. A partition 23 whose outer margin is secured in the joint between the element 15 and the cylinder 13 and whose inner edge is joined to the tube 21 and a partition 24 whose outer margin is secured in the joint between the head 14 and the cylinder 13 and whose inner edge is joined to the tube 20 to divide the interior of the compartment defined by the tubes 20 and 21 and the cylinder 13 and its upper and lower heads into three chambers 25, 26 and 27. The upper chamber 25 communicates with the duct 20—21 through orifices 28 in the tube 21 and with the orifices constitutes a simple resonator. The lower chamber 27 communicates with the intermediate chamber 26 through a tube 29 which is secured in an opening in the partition 24 and the intermediate chamber 26 communicates with the duct 20—21 through the annular aperture 22. The chamber 27, the tube 29, the chamber 26 and the aperture 22 constitute a compound resonator.

The filter element 11 encircles the crown of the element 15 with its lower end seated in the channel 16 in the brim thereof and its upper end projecting somewhat above the top of the crown. The filter element consists of coaxial inner and outer cylindrical screens 30 and 31 whose interspace is filled with a suitable liquid-coated filter medium 38 such as that disclosed in the Webb application Serial No. 752,232 which was filed on November 9, 1934. The rim of the cap 12 rests on the upper end of the filter element 11 and has on its outer edge a downwardly projecting flange which embraces the upper end of the filter element. The portion of the cap between its rim and its center is pressed outwardly to accommodate an annular pad 32 of sound absorbing material, such as felt, which is held in place by crossed arms 33 and 34 which are secured to the rim and center of the cap. The filter element is firmly clamped and held in place between the cap and the brim of the element 15 by a nut 35 threaded on a stud 36 carried by a yoke 37 which is secured to the top of the crown of the element 15 and extends across the opening therein. However, as Figure 3 indicates, the cap 12 may be lifted off the filter element 11 and the filter element lifted off the body 10 when the nut 35 is unscrewed. The consequent ease with which the filter element may be separated from the body and the cap, of course, facilitates servicing of the filter element.

The air cleaner and silencer assembly which is shown in the drawing was designed for installation on an internal combustion engine with the

outer end of the tube 26 connected to the air intake tube of the carburetor so that it cleans the air that enters the carburetor and silences the so-called intake noises of the engine. Although the assembly has been described as if it were to be installed in the upright position in which it is shown in the drawing, it may, of course, be installed upside down or in any other position. If the assembly is installed so that the filter element would be exposed directly to the blast of the engine cooling fan or any other current of air, there may be provided, as shown in the drawing, a baffle 38 to shield it therefrom.

When the assembly is installed in the described manner and the engine on which it is installed is operating, the suction of the engine draws air from the atmosphere through the filter element 11, over the crown of the element 15 and through the opening in the top of it and the duct 26-21 into the carburetor and cylinders of the engine.

The filter element, of course, frees the air which passes through it of foreign matter. The pad 32 of sound absorbing material in the cap 12 eliminates components of the intake noises which are due to sound waves of high frequencies. The hiss-gap 18 eliminates components of the intake noises which are due to sound waves of high frequencies which are not sufficiently attenuated by the pad of sound absorbing material. The resonators 25-28 and 27-29-26-22 are tuned in the manner set forth in the Wilson application Serial No. 470,700, filed July 25, 1930 and eliminate components of the intake noises which are due to sound waves of lower frequencies.

35 I claim:

1. In an appliance of the class disclosed, a member shaped generally like a brimmed hat with an orifice in the top of its crown, an annular filter element of which one end is seated on the brim and encircles the crown of the generally hat shaped member, a cap whose rim is seated on the other end of the filter element and spaced from the generally hat shaped member solely thereby, and means by which the filter element is releasably clamped between the cap and the brim of the generally hat shaped member including a yoke whose ends are secured to the top of the crown of the hat shaped member and a threaded member which extends through the cap and is connected to the yoke. 15

2. In an appliance of the class disclosed, a member shaped generally like a brimmed hat with an orifice in the top of its crown and an annular channel in its brim, an annular filter element of which one end is seated in the annular channel 20 in the brim and encircles the crown of the generally hat shaped member, a cap whose rim is seated on the other end of the filter element and spaced from the generally hat shaped member solely thereby with a flange on its rim which encircles the end of the filter element on which the cap is seated, and means by which the filter element is releasably clamped between the cap and the brim of the generally hat shaped member, including a yoke whose ends are secured to the top 25 of the crown of the generally hat shaped member, a stud which is carried by the yoke and extends through the cap, and a nut threaded on the stud. 30
